ARMAND MAX MAYER, OF LEVALLOIS-PERRET, FRANCE.

TELEMECHANIC INSTALLATION.

Application filed September 23, 1920. Serial No. 412,166.

To all whom it may concern:

Be it known that I, ARMAND MAX MAYER, engineer, citizen of the French Republic, residing at Levallois-Perret, department of 5 Seine, France, have invented certain new and useful Improvements in Telemechanic Installations, of which the following is a specification.

This invention relates to telemechanic installations, that is installations wherein a movement is to be effected at a distance, by using on the one hand a transmitting agent such as electricity transmitting its effect either by wires or Hertzian waves, and using 15 at the other hand for the production of the actual movement the current of a local source of electricity.

Its object is to improve the preciseness of action of such installations.

20 It consists principally in such an arrangement and such usage of the elements combined in the arrangement that the resulting effect of the tele-signal becomes complete only at the moment of the ceasing of said 25 tele-signal, and only if the current determined by the tele-signal has acted in the same direction during a protracted period.

It consists moreover in the application of arrangements of the above nature to the tele- 30 mechanic correction of the indications of moving apparatus such as meters and especially clocks, and it consists finally in other arrangements hereinafter referred to, with reference to the accompanying drawings 35 showing examples of embodiment and of application, and in which drawings:—

Fig. 1 is an axial diagrammatic section of one element of the installation.

Fig. 2 shows diagrammatically in an installation the application of the element shown in Fig. 1 as used for the abrupt correction of clocks by means of Hertzian waves.

Fig. 3 shows in a similar view another 45 form of installation for the same purpose and wherein the correction is effected abruptly and in two steps.

Fig. 4 shows in a similar view an installation having the same object but wherein 50 the influence of the setting obtained through the telemechanic intervention acts all the time.

With reference to Fig. 1, 1 is the reciprocal core of a solenoid relay the winding 55 2 of which is under the influence of the electric signals sent out from a distance. The

core 1 is arranged to travel through a substantial part of its stroke before its projection 3 comes in contact with a contact-lever 4 pivoted on a bracket 5. Such stroke can 60 be traveled only under the action of a protracted current acting for a considerable time in the same direction and the tele-signal is arranged to provide such a current. Thus the danger of the reacting of the contact-device to parasitic currents, or signals not intended for the working of the solenoid-relay, is obviated. The said danger may be still lessened in causing a mechanical resistance to hinder the upward movement of the 70 core 1 so that said movement will fully take place only under currents of a very constant and protracted character, the descent of the core being left unhindered.

The contact-lever 4 is pivoted to a fixed 75 isolated bracket 5. The pointed end of lever 4 lies in the path of the projection 3 and opposite to the other end of the lever 4 there is a contact 6 fixed to an elastic plate 7. A coil spring 8 holds the lever 4 normally in a 80 horizontal position, though permitting the same to be moved by the projection 3 either up or down.

During the upward motion of the projection 3 there will be no contact between lever 85 4 and contact 6 as the pointed end of the lever will be pulled up and fall down again, the core itself remaining—as long as the tele-signal lasts—in the highest position 90 which it can occupy; but at the precise moment when the tele-signal ceases, or else the current ceases in the winding 2 of the solenoid-relay, the core 1 will fall down and cause the lever 4 to press against contact 6 in lifting the same, finally the core 3 continuing its fall and the edge of the projection 3 passing the lever 4, the latter will resume its horizontal position of rest in which there is no contact between lever 4 and contact 6.

The short duration of contact described 100 is utilized in order to effect the telemechanic movement which is intended, in using the energy of a source of electricity the poles of which are connected to lever 4 and contact 6.

Such device as described acts at the end 105 of a protracted tele-signal, or the ceasing of a protracted current emitted from the controlling station.

Such device may be applied either for the 110 setting to the zero-point of apparatus which is not in movement such as for instance, a

thermostat, or for the correction of the showing of an apparatus in motion such for instance as a clock.

In the latter case the relay shown in Figure 1, may be applied to the installation shown in Fig. 2, intended for the correction of a clock by wireless signals and wherein 9 is the aerial for the reception of the electromagnetic waves, 10 is an amplifying and detecting device for the waves, which produces for instance a direct current actuating a sensitive relay 11 of any convenient type which in its turn acts on a special retarded relay 12 which is identical to the solenoid 10 produced during 6 seconds a current of constant intensity in the windings of the different relays 12). At the precise moment predetermined, for the end of the tele-signal (for instance at each midnight) 70 the signal of say six seconds ceasing, the positions of the hands of all the clocks are corrected.

Statics (or else strays or other parasitic currents) of the installations may have a 75 great intensity and cause the core to raise somewhat for a moment but owing to their short duration they will not raise it to the height of the lever 4, so there is no danger of an undesirable correction being effected. 80

In order to prevent needless functioning (originated by parasitic currents) of the sensitive relay 11, its circuit is ordinarily interrupted and will be closed by the hand 18 of the clock at about thirty seconds before 85 the hand comes to the time position which is to be corrected and opened at about thirty seconds thereafter. The principle of the conservative device, though known, is illustrated in Fig. 2 wherein the hand 18 of 90 the clock in coming in contact with the contact segment 19, purposes the receiving station for action.

Relays of retarded action are known in themselves, also special means for their retardation such as springs, dashpots or devices having an analogous effect. The new point in the special retarded relay is that it causes the correction of the installation at 95 the end of the time signal or other signal 100 sent out of the central controlling station.

The time signal may of course in the case of an existing wiring system be transmitted by wire rather than by wireless, (this being the case for instance for a railway company) the function of the special retarded relay being otherwise the same. 105

A warning device may be added which shows when, in consequence of a disorder in the installation, the setting of the hands has not been effected. 110

In installations in which the setting of the hands of clocks is done abruptly the setting mechanism used may be any system other than that which has been described, 115 having other principal elements than the correcting cam of the form of a heart.

In installations of a slightly varied type the ordinary type of retarded relay can be used (which acts at the moment when the core raises to its highest position). Such installation is seen in Figure 3 and the common retarded relay thereof is designated by 120 20. The setting of the hands in such an installation will occur not at the end of the 125 time signal which may be of 5 seconds but at the end of the raising of the core of said common retarded relay, which may be effected in about three seconds, thus the correction will occur two seconds too early, 130

The conditions of functioning of the installation are as follows.

First of all the intensity of the current derived from the amplifier 10 must be sufficient (say one milli-ampere) in order to produce a contact in the sensitive relay 11. Second its duration must be long enough (say three seconds) in order to raise completely the core 2 of the special retarded relay 12. The tele-signal itself must have a duration longer than the said three seconds in order that there may be a sufficient security for the complete raising of the core. When the tele-signal lasts for six seconds and when the installation consists of a great number of clocks to be set, all the cores 2 of the different special retarded relays of the different clocks are certainly on their highest point when the tele-signal ceases (after hav-

and an error of two seconds would be committed. Therefore in such installations there is adjoined, to the mechanism of the correcting cam of the form a heart, a secondary additional mechanism permitting the clockwork to be stopped at the moment of the action of the correcting cam and to be set in motion again after the falling down of the core of the common retarded signal relay 5 20. This function can easily be obtained in utilizing the beginning of the stroke of the finger 17 to stop the clockwork and the final part of the backstroke of said finger to cause it to resume its going, that is the final part 10 15 of the restoring stroke of the armature of the final relay 16 causes for instance the motion of the pendulum of the clock, having been formerly disconnected, to be reconnected with the clockwork. 20 25

20 The disengaging and engaging mechanism thus added to the clock makes the use of the common type of the retarded relays possible, without altering the general type of the installation, the corrected movement of the clock works beginning only at the end of the time-signal as before.

30 The only difference is that in the first case correction is effected in one single step, the hand alone being corrected, the clock going all the time, and in the other that the clock is first of all stopped then the hand corrected (first step) and finally the clock caused to resume its going (second step).

35 The mechanism for stopping and restarting the clockwork may be of any known kind, it may for instance as already explained consist in disconnecting and reconnecting the otherwise undisturbed motion of the pendulum with the remaining clockwork the pendulum itself being kept electrically moving and being in such case the real motor of the clockwork.

40 In the Figs. 2 and 3 means have been shown to correct abruptly the position of the hands without correcting the going of the clock work itself, Fig. 4 shows schematically a part of the installation for the telemechanic correction of the going of the clock itself consisting for instance in the 45 daily interference with the conditions of swinging of the pendulum.

45 The pendulum 21 (Fig. 4) may be fitted with any suitable device for influencing its period of oscillation, and consisting in the 50 regulating of a feeble electric current passing in the windings of a stationary electromagnet 22, the extremity of the pendulum being fitted with a permanent magnet 23 one of the poles thereof passing in the proximity of one of the poles of the said electromagnet 22. If the thus juxtaposed poles are of the same name the time of oscillation 55 of the pendulum is increased; when there is no current in the electromagnet 22 the 60 pendulum keeps its natural value, and if the

current is reversed in the windings of the electromagnet 22 the time of oscillation of the pendulum is shortened. These influences are dependent in acting on the intensity of the current circulating in the electromagnet 22 in either direction. A suitable device consisting of a double rheostat and two sources of current able to perform this function may be utilized having a contact arm 24 having a non-contact middle position 70 (as drawn in full lines), with the possibility of several positions for sending positive current of increasing intensity in the windings of the electromagnet 22 (position of arm drawn in dotted lines) and the possibility of 75 several positions for sending negative current (position of arm drawn in dot and dash lines).

80 The telemechanic intervention changes daily the position of the contact arm 24, 85 said position remaining exchanged between two telemechanic interventions.

85 The contact arm 24 is rotated at the occasion of a telemechanic intervention, either to the left or to the right, by a convenient 90 means for instance by motor 25. The current for this motor comes for instance from the two opposite junctions 26 and 27 of a Wheatstone bridge, the other two junctions 28 and 29 being connected to a source of current 30 95 with the interposition of a contact-gap 31 which commonly arrests the current from flowing through the Wheatstone bridge. The said contact gap 31 is closed only during the time of the totally raised position of a 100 common retarded relay 20. The bridge is unbalanced one of its resistances (32), being less than the others. Therefore when the contact gap 31 is closed the armature of the little electric motor 25 will receive the 105 current in the direction indicated by the arrow 33 (drawn in full lines). The resistance 34 of the Wheatstone bridge can in certain positions of the hand 18 of the clock be short circuited by a time contact 35 110 and when this short circuit is actually effected the Wheatstone bridge will be put out of its former condition and the electric motor 25 will receive a reversed current the direction of which is indicated by the dotted 115 arrow 36.

120 If the signal arrives before the hand 18 touches the time contact 35, the electric motor 26 will turn in, say, the clockwise direction and effect the correction of the position of the contact arm 24 in such a direction as to accelerate the oscillations of the pendulum, if on the contrary the hand 18 is already on the time contact 35 when the signal arrives, the electric machine 25 will 125 turn in the opposite say anticlockwise, direction in causing such displacement of the arm 24 as to slow down the oscillation of the pendulum. The intervention of the electric motor 25 begins at the moment of the 130

total raising of the core of the common retarded relay 20, such as seen in the Fig. 4, providing that an ordinary retarded relay is used, and said intervention will cease at the 5 moment of the ending of the time tele-signal. At such moment the contact gap 31 will be open again and the flowing of current through the Wheatstone bridge arrested. If the special retarded relay 12 10 (shown in Fig. 1) is used in the installation of Figure 4, the tele-intervention will last as long as the airgap between contact 6, and lever 4 of said relay 12 is closed during the descent down of the core I. The contact-arm 24 remains in the corrected position until the next telemechanic intervention takes place. If the clock is correctly 15 regulated there will be in principle just as long a time duration (at the occasion of one telemechanic intervention) during which the 20 electric motor 25 turns to the right as there will be a time duration during which said electric motor turns to the left, so that the position of the arm 24 remains practically 25 unvaried. With the installation shown in Fig. 1 it is important to use retarded relays having an exactly regulated time for rising. This condition is unimportant when in the 30 same installation special retarded relays such as shown in Fig. 1 are utilized instead of the common retarded relay 20 shown on said Fig. 4.

I am aware that the regulation of clocks by means of telemechanic arrangements has 35 been made before, I therefore do not claim the installation broadly but,

I claim:

1. In a telemetric system for clock regulation by Hertzian regulating signals, a regulating means for imposing regulative interference upon a moving part of a clock, actuating means for said regulating means comprising an electro-magnet energized in response to Hertzian tele-signals, an armature 40 therefor having a wide range of movement, said regulating means being situated at such point in the path of movement of said armature as will be passed by the latter in response to protracted energization only of said electro-magnet, said means being actuated by said armature on its return movement to terminate the regulative interference upon cessation of the Hertzian tele-signal.

55 2. In a telemetric system for clock regulation by Hertzian regulating signals, regulating means for imposing regulative interference upon a moving part of a clock, actuating means for putting said regulating means into and out of operation comprising an electro-magnet energized in response to Hertzian tele-signals, an armature for said magnet having a range of movement proportional to the duration of energization of said 60 electro-magnet, said regulating means be-

ing located at such point in the path of movement of said armature as will be passed by said armature in response to protracted energization only of said electro-magnet, said regulating means being actuated solely 70 through the kinetic energy of said armature on its return movement, to terminate said regulative interference at the cessation of the Hertzian tele-signals.

3. In a telemetric system for clock regulation by Hertzian regulating signals, regulating means for imposing regulative interference upon a moving part of a clock, said means comprising a circuit including a solenoid and a source of current, a switch in 75 said circuit, actuating means for closing and opening said switch comprising an electro-magnet energized in response to Hertzian tele-signals, an armature for said electro-magnet having a range of movement proportional to the duration of energization of 80 said electro-magnet, said switch being located at such point in the path of movement of said armature as will be passed by said armature in response to protracted energization only of said electro-magnet, said switch being opened solely through the kinetic energy of said armature on its return movement to terminate said regulative interference 85 at the cessation of the Hertzian tele-signal. 90

4. In a telemetric receiving installation for regulation of clocks by Hertzian tele-signals, a retarded relay energized in response to Hertzian tele-signals, a clock having a moving part, regulating means to regulate the movement of said moving part, an electric circuit divided into branches having unequal resistance, said regulating means being connected into both branches of said 100 circuit, a switch in said circuit controlled by said retarded relay, said switch being closed, held closed and opened by said relay during the period of duration of said Hertzian tele-signal, a second switch in said 105 circuit controlled by the moving part of said clock and arranged to be open during the period when the tele-signal is not awaited and to be closed at about the mid period of the duration of the Hertzian tele-signal, said 110 contacts when closed short circuiting the resistance in the branch of said circuit having the greater resistance so as to shift the preponderance of resistance to the other branch 115 and reverse the direction of current through said regulating means, said regulating means contacts when closed short circuiting the resistance in the branch of said circuit having the greater resistance so as to shift the preponderance of resistance to the other branch 120 and reverse the direction of current through said regulating means, said regulating means acting to accelerate or slow down the movement of the moving part of the clock according to whether the second switch is closed or open at the time of closing of the first switch 125 by said retarded relay.

5. In a telemetric receiving installation for the regulation of clocks by Hertzian tele-signals, a clock work, an electro-magnetic means for accelerating or slowing down said 130

clock work, said electro-magnetic means being common to two circuits of opposite polarity, a variable resistance for each circuit, a switch for selectively closing either circuit, 5 a reversible electric motor for actuating said switch to close either circuit, means for reversing the direction of current through said motor comprising a Wheatstone bridge having an unbalanced limb of less resistance 10 than the other limbs, a source of current connected to opposite junctions thereof, a retarded relay in circuit with said source of current and controlling switch contacts, said contacts being closed during part of the up 15 stroke of the armature of said relay and closed also during part of the return stroke thereof, a circuit connected to the other opposite junctions of the Wheatstone bridge and including the electric motor, switch contacts in said circuit operated by said clock work and arranged to be closed about the time of expectation of said tele-signal, said switch functioning to short circuit a limb of said Wheatstone bridge so as to reverse the current through said electric motor. 20 25

In testimony whereof I have hereunto set my hand in presence of a witness.

ARMAND MAX MAYER.

Witness:

VICTOR MARENDSWSKI.
